[57] CLAIM

The ornamental design for a chair, substantially as
shown and described.

DESCRIPTION

FIG. 1 is a rear perspective view of the chair;
FIG. 2 is a side elevational view of the chair taken on
the side exposed in FIG. 1;

FIG. 3 is a side elevational view of the chair taken on
the opposite side from that shown in FIG. 1; and
FIG. 4 is a front perspective view of a modified form of
the chair shown in FIG. 1.

The characteristic feature of the article resides in the
combination of the seat having a generally oval end
configuration with the back having an oval end configura-
tion having its long axis extending transversely to the
long axis of the seat.
